UNITED STATES PATENT OFFICE.

HAROLD W. BROWN, OF WILKINSBURG, PENNSYLVANIA, ASSIGNOR TO WESTINGHOUSE ELECTRIC AND MANUFACTURING COMPANY, A CORPORATION OF PENNSYLVANIA.

ELECTRICAL GROUND-DETECTOR.

1,112,438.

Specification of Letters Patent. Patented Oct. 6, 1914.

Application filed October 17, 1912. Serial No. 726,280.

To all whom it may concern:

Be it known that I, HAROLD W. BROWN, a citizen of the United States, and a resident of Wilkinsburg, in the county of Allegheny and State of Pennsylvania, have invented a new and useful Improvement in Electrical Ground-Detectors, of which the following is a specification.

My invention relates to means for detecting the presence of grounds on electrical distributing circuits, and it has for its object to provide a simple and economical ground detector which shall have a large torque so that it will be positive in operation, and which may be adapted with little or no change for use upon any circuit irrespective of its voltage, and whether it is an alternating or direct current circuit.

Figure 1 of the accompanying drawing, is a face view of a ground detector constructed in accordance with the present invention. Fig. 2 is a transverse sectional view through the instrument of Fig. 1. Fig. 3 is a diagrammatic view of the electrical connections of the instrument when employed in connection with a low voltage circuit, and Fig. 4 is a similar view showing the connections when the instrument is employed in connection with a high voltage circuit.

The instrument comprises an annular laminated core member 1 having substantially equally spaced inwardly extending radial polar projections 2, 3 and 4, that are surrounded respectively by coils 5, 6 and 7. The core member is secured in any suitable manner to a plate or support 8, that is, in turn, secured to the back or base 9 of a casting 10 that incloses the operating parts of the instrument, and is provided with a glass or other transparent front 11. Between the polar projections 2, 3 and 4, and within the field of influence thereof, is an armature 13, the polar axis of which is normally disposed transversely to the polar axes of the projections 2, 3 and 4 and substantially at right angles thereto. The armature comprises a magnetizable bar 14 upon the opposite ends of which spherical plates or heads 15 are mounted, the heads being shaped to present polar faces adjacent and corresponding respectively to the polar projections 2, 3 and 4. The armature is mounted so as to be capable of movement in any direction from its normal position, as shown in the drawing, and to this end the bar 14 com-

prises a yoke 16 that surrounds and is pivotally connected to shaft 17, having bearings at its ends in a stationary yoke or bracket 19. The cross bar 14 of the armature is surrounded by two spaced coils 20 and 21 that are located upon opposite sides of the shaft 17, and are also supported by the yoke or bracket 19, the said coils being thus stationarily mounted. The openings through the coils, however, are of sufficient diameter 65 to permit of entire freedom of movement of the said bar, and the spaces between the abutting faces of the coils are also sufficient to permit of freedom of rotation of the shaft 17. 70

When the instrument is employed in connection with a low voltage circuit, the connections are as shown in Fig. 3, in which terminals of the coils 5, 6 and 7 are respectively connected directly to distributing circuit conductors 22, 23 and 24, and the remaining terminals of the said coils are connected together, and to one terminal of the magnetizing winding for the armature, the other terminal of which is connected to the ground. Under normal conditions, with this arrangement of the connections, substantially equal currents traverse the coils 5, 6 and 7 from the distributing circuit through the coils 20 to the ground, and the armature consequently remains in a central position. However, the grounding of any one of the distributing circuit conductors will result in unequal flows of current through the coils 5, 6 and 7, followed by a movement of 80 the armature in a direction corresponding to, and indicative of, the grounded conductor. This will be understood by assuming that a ground occurs upon the conductor 24, in which case greater currents will traverse the coils 5 and 6 than the coil 7, which is connected to the grounded conductor, because of the reduced potential applied to the coil 7. This results in an unbalancing of the torques upon the armature, which, accordingly, moves in a direction to indicate that the conductor 24 is connected to the ground. 95

In Fig. 4, transformers 26, 27 and 28 respectively are interposed between the ground detector and the distributing circuit 29—30—31 for the purpose of reducing to a safe value the potential upon the terminals of the instrument, the common or neutral terminal of both the primary and 110

secondary windings of the said transformers being connected to the ground. The remaining terminals of the secondary windings of the transformers are connected respectively to terminals of the coils 5, 6 and 7 of the ground detector, and as in Fig. 3, the remaining terminals of the said coils are connected together and to one terminal of the winding 20, the other 10 terminal of which is connected to the ground and to the common terminal of the secondary windings of the transformer. If, when the connections are as shown in Fig. 4, a ground occurs upon one of the distributing 15 circuit conductors, unequal currents will traverse the primary windings of the transformers, and also the secondary windings, with the result that the armature of the ground detector is moved in a direction to 20 indicate the grounded conductor, in a similar manner, to that set forth in connection with Fig. 3.

By reason of the fact that the operating torque of the instrument is produced by 25 electrical magnet windings, and that each of the said windings is provided with a magnetizable core, it will be readily understood that the torque is high and may be made sufficient to effect positive and reliable 30 movements of the armature. The instrument also permits of the employment of transformers when it is used in connection with an alternating current circuit and accordingly may be adapted for use with circuits of any voltage. 35 While, at the same time, the voltage upon the terminals of the instrument may be relatively low, so that there is no danger to operators while the instrument is in use, and no difficulties are experienced in providing 40 adequate insulation. Moreover, the degree of movement of the armature indicates quite accurately the voltage between the grounded conductor and the ground, and thus obviates the necessity of employing a separate 45 voltmeter for obtaining this information.

I claim as my invention:

1. A ground detector comprising relatively universally movable members, one of which is provided with a plurality of coils 50 having a common terminal, and the other of which is provided with a coil that is connected to the common terminal of the aforesaid coils.

2. A ground detector comprising relatively universally movable members, one of which is provided with a plurality of coils 55 having a common terminal, and the other of which is provided with a coil that is connected between the said common terminal and the ground.

3. The combination with a distributing circuit, of a ground detector comprising relatively universally movable members, one of which is provided with a plurality of coils

having a common terminal and the remaining terminals connected respectively to the distributing circuit conductors, and the other member of which is provided with a coil that is connected between the common terminal of the aforesaid coils and the ground.

4. The combination with a distributing circuit of a ground detector, comprising relatively universally movable members, one of which is provided with a plurality of coils 75 respectively corresponding to and associated with the distributing circuit conductors, the said coils having a common terminal, and the other member of which is provided with a coil that is connected to the common terminal of the aforesaid coils.

5. The combination with a distributing circuit of a ground detector, comprising relatively universally movable members, one of which is provided with a plurality of 85 coils respectively corresponding to and associated with the distributing circuit conductors, the said coils having a common terminal, and the other member of which is provided with a coil that is connected between the common terminal of the aforesaid coils and the ground.

6. A ground detector comprising a stationary member provided with a plurality of field coils, a universally movable armature within the magnetic fields of said coils, and a stationary magnetizing coil for the 95 said armature.

7. A ground detector comprising a stationary member provided with a plurality of 100 field coils having a common terminal, a universally movable armature within the magnetic field of the said coils, and a stationary magnetizing coil for the armature that is connected to the common terminal of the 105 aforesaid coils.

8. A ground detector comprising a stationary member provided with a plurality of field coils having a common terminal, a universally movable armature within the 110 magnetic field of the said coils, and a stationary magnetizing coil for the armature that is connected between the common terminal of the aforesaid coils and the ground.

9. A ground detector comprising a core 115 member having a plurality of opposing polar projections, a coil upon each of the said projections, a universally movable armature within the magnetic fields of the said coils, and a stationary magnetizing coil for 120 the armature.

10. A ground detector comprising a core member having a plurality of opposing polar projections, a coil upon each of the said projections, a universally movable armature within the magnetic fields of the said coils, the polar axis of the armature being 125 normally disposed transversely to the polar

axes of the polar projections from the core, and a stationary magnetizing coil for the armature.

11. A ground detector comprising a core member having a plurality of opposing polar projections, a coil upon each of the said projections, a universally movable armature within the magnetic fields of the said coils, each pole of the armature comprising 10 as many branches as there are poles upon the core, and a stationary magnetizing coil for the armature.

12. A ground detector comprising relatively movable members, one of which is 15 provided with a plurality of coils having a common terminal, and the other of which is provided with a coil that is connected to the common terminal of the aforesaid coils, the fluxes produced by the said coils coöperat-

ing to produce relative movement of the said 20 members.

13. A ground detector comprising relatively movable members, one of which is provided with a plurality of coils having a common terminal, and the other of which is 25 provided with a coil that is connected between the said common terminal and the ground, the fluxes produced by the said members coöperating to produce relative movement of the said members. 30

In testimony whereof, I have hereunto subscribed my name this 27th day of Sept. 1912.

HAROLD W. BROWN.
